UNITED STATES PATENT OFFICE.

WILLIAM REED McCATHRAN, OF WASHINGTON, DISTRICT OF COLUMBIA.

INTERMITTENT INDUCTIVE TRAIN-CONTROL SYSTEM.

Application filed October 24, 1923, Serial No. 670,547. Renewed March 12, 1927.

This invention relates to improvements in block signalling and train control systems.

One of the objects of this invention is to provide a train device which operates only when opposite a track device and preserves the setting then given until it passes over a succeeding device upon the track.

Another object is to provide a track device which is simple, has no moving parts save those controlled by the track relay and the semaphore, and is adapted for use with traffic moving in either or both directions.

Another object is to provide means for permissive control in the train circuit, whereby the speed of the train may be reduced by the engineer in accordance with the signal indication at the semaphore, but if not so reduced, a positive brake application will be given.

Another object is to make the train and track apparatus electrically independent but magnetically cooperative when the train elements are in proper relation to the track elements.

Another object is to provide a train system such that a positive act by the engineer is required to enable the train to enter a block when the block is in the "danger" or "caution" condition.

Another object is to dispose the train elements of such a system so that a failure of any part will cause an operation of said elements similarly to the "danger" position or condition of the track semaphore apparatus.

Another object is to incorporate in the train circuits a speed-controlling means to limit the permissive train speeds corresponding to the condition of the block about to be entered.

A further object is to render such systems automatic in operation upon the occurrence of foreseen conditions and to cause a "danger" indication and operation in the event of lack of battery power, breakage of a rail or of the apparatus, or other unforeseen conditions.

With these and other objects in view as will appear from the following specification and claims, one exemplification of execution of the invention is shown on the accompanying drawings, in which:

Fig. 1 is a diagrammatic presentation of the train and track circuits in a normal or "clear" position.

Fig. 2 is a detail of the governor device and its contacts.

Fig. 3 is a detail of a signal semaphore and its switch mechanism.

Fig. 4 is a detail of the track and train elements in cooperating position.

Primarily, this system comprises the train elements and the track elements, each of which has accessory apparatus and connecting circuits. The track elements are a pair of magnets placed on or near the right-of-way: induction coils on them have currents induced therein by the passage of the train elements thereover. These track coils are connected together as described hereinafter. The train elements are magnetized by a current from a suitable alternator, and are connected with a speed-governor, air release valve in the brake-pipe, a control relay, and a bank of signal lamps.

The fundamental indications are "danger" (red lamp with emergency stop or very low speed), "caution" (yellow lamp or medium speed), and "safe" (green lamp and a predetermined maximum speed).

When the train enters a block, the train elements pass over the track elements of that block. If the block ahead is clear, the track elements are connected in series, so that the one train element induces a current in the corresponding track element coil, this induced track current magnetizes the other track element, which in turn induces the controlling current in the second train element to set or maintain the train apparatus at "safe." If the block ahead is in a non-clear condition but the train may pass through it at a slower speed, the track semaphore indicates "caution," and a switch on the semaphore arm reverses the connections of the two track elements. As the train passes over them, the induced track current passes as before, but induces a current in the reverse direction in the train element coil, which causes the train apparatus to indicate and operate at "caution." In the event of broken rails, a train immediately ahead, failure of track battery, or other trouble, the two track elements are not connected together, and no current is induced in the second track element. The train apparatus then falls to a neutral position and a "danger" indication and operation is effected.

After this summary, the invention will now be described in relation to the draw-

ings which present one exemplification of the features of this intermittent inductive train control system.

Train apparatus.—On the engine or other suitable part of the train, operated by steam, electricity, etc. (hereinafter referred to as the locomotive) is placed an alternating current generator A, which delivers a current of about 32 volts to the wires 40, 40', and 41, 41'. It has been found that frequencies as low as 25 cycles may be used with separately driven machines. This alternator may be driven by a separate steam or air turbine, or belted to the engine wheels. The wires 41, 41' lead to the coil 42 of an alternating current electromagnet forming a dynamometric relay B. This relay has a plurality of contact blades 1, 2, 3, 4 insulated electrically from each other but connected mechanically for simultaneous operation to be brought into any of the three positions R, C, and L, corresponding respectively to the right, center, and left positions in the drawing, in which the contact blade 1 makes contact with points 13, 14, or 15, and the other blades make similar contact with their respective corresponding points.

Upon the locomotive is likewise provided a governor C driven from a bogey wheel or other appropriate rotating member so as to be rotated at a speed corresponding to the train speed. This governor is shown in Fig. 2 as provided with a circuit closing bar c engaging with selective sets of a number of contacts, depending upon the train speed. On the drawing, the centrifugal governor is provided with three such contacts at H, M, and L, corresponding to high, medium, and low train speeds. The contact plate h opposite H and M is connected by a wire 43 to an alternating current electromagnet D. The other terminal of electromagnet D is connected by wires 44, 45 and 41 to one side of generator A. The electromagnet D has a plunger 150 formed with two opposing valve seats, a large one 151 and a small one 152, designed for alternate respective lodging on seats 153 and 154 in the walls between the main bore or cylinder chamber 155 and the side chambers 156 and 157 of an electromagnetic air valve. The actuation of the plunger 150 by spring 151' upon de-energization of the solenoid D permits the compressed air in the branch pipe 158 connected to the train pipe to pass the valve 151 and enter the main bore chamber or cylinder 155; in the latter it forces piston 159 upwards and permits the compressed air to escape from train pipe 160 through the valve 161 into the pipe 162. This servomotor type of control is preferred, but in small installations, the compressed air in pipe 158 may be allowed to escape directly to the atmosphere, to accomplish the same end.

65 The contact plate l opposite contact L is

connected by wires 46 and 47 to a push button K mounted at an easily accessible point of the locomotive cab. From push button K, a wire 48 leads to one terminal of the resetting magnet RM, and a wire 49 leads to one stationary contact 50 of the circuit maker and breaker 25. Two moving contacts 51 and 52 of this circuit breaker and maker 25 are mechanically connected for simultaneous operation by the electromagnet RM, and are both connected electrically by wire 53 to wire 46. The other stationary contact 52' of the circuit breaker 25 is connected by a wire 49' to wire 43 and thus to one terminal of electromagnet D.

Returning to the groups of contacts of relay B, the right-hand contact 13 opposite the moving blade 1 which receives current from wire 40' is connected by a wire 56 to a green lamp G, the center contact 14 by a wire 57 to a red lamp R, and the left-hand contact 15 by a wire 58 to a yellow lamp Y. The other terminals of the lamps are connected by the return wire 45 to the generator A. The lamps are located in an easily visible location in the locomotive cab.

The second moving blade 2 likewise receives current from wire 40'. Its right-hand contact 16 is connected by a wire 59 to the contact plate H of the governor C; its center contact 17 by a wire 60 to the plate L, and its left hand contact 18 by a wire 61 to the plate M.

The third moving blade 3 is connected by a wire 64 to the coil 65 of a train element F. Its right-hand contact 19 is connected by a wire 62 to the left hand contact 24 of the fourth group and to the return wire 40 leading to the generator A; the center contact 20 by a wire 63 to the center contact 23 of the fourth group; and the left-hand contact 21 by a wire 66 to the supply wire 40', and by wire 67 to the right-hand contact 22 of the fourth group.

The fourth moving blade 4 is connected by a wire 68 to the other terminal of the train magnet F. The stationary contacts 22 and 24 of this moving blade 4 are connected as noted above.

The outer four contacts of the third and fourth groups, with their moving blades, therefore function as a reversing switch, i. e. when the moving blades are all in the right-hand position, the circuit from alternator A passes by wires 40' and 67 to contact 22, moving blade 4, wire 68, winding 65 of magnet F, wire 64, moving blade 3, contact 19, wires 62 and 40, back to the alternator; and when the blades are in the left-hand position, the circuit is formed from alternator A by wires 40' and 66 to contact 21, moving blade 3, wire 64, winding 65 of magnet F, wire 68, blade 4, contact 24, wires 62 and 40, back to the alternator A.

The train magnets E and F are disposed

at proper locations on the locomotive, such as between the wheels W, as shown in Fig. 4, so as to be brought over the track elements X and Z at predetermined points of the block.

The train magnet F comprises the coil 65 wound about an iron core 5—6. This core has legs 6—10 and 5—9 at right angles to the main portion 5—6, with inwardly directed projections 7 and 8 which leave between them an air gap at 69. A coil 35 is wound around these projections and surrounding the air gap between them. The terminals of this coil 35 are joined by wires 70 and 71 to a coil 34 disposed as the supplemental coil to the coil 42 of the dynamometric relay B.

The auxiliary train element E has an iron core 11—26—27—12 of inverted U shape, 29 with a winding thereon fed directly by the generator A through the wires 40, 40', at all times.

Track elements.—The track T is divided into blocks of suitable length by insulating members 100, 100'. In the drawing, the train is presumed to be moving in the direction of the arrow, i. e. from left to right. It is therefore the condition of occupancy of the right-hand block which shall govern the control of the train in the left-hand block at its entry into the right-hand block. The rails 101 of the right-hand block receives from the battery 103 a current which, if no train be occupying this block, flows as usual towards the insulation 100, thence by a wire 104 to a coil 105 of the track relay TR, thence by a wire 106 of the relay to the rail 101', and back to the battery 103. This relay TR has two moving blades 107 and 108, 40 with respective stationary contacts 132 and 133, from which wires 109 and 110 lead to the coil 111 of a track magnet Z. The moving contact 107 is connected to the outer contacts 112, 112' by wire 113, and the contact arm 108 by a wire 115 to the inner contact 114 of a pole-changing switch N, the arm 116 of which is connected by a wire 117 to the contact arm 118 of a controlling switch P. This arm 118 may occupy any of three positions on the respective contacts 119, 120, 121, of which 119 and 120 are joined by a conducting plate 122 or may be formed as a single contact, and 121 is a dead or open-circuit point. The plate 122 is connected by a wire 123 to the coil 124 of an auxiliary track magnet X. The wire 116' of the switch N is connected by a wire 125 to the other terminal of coil 124.

The contacts of the switches N and P are placed on the rotatable drum W on the shaft of the semaphore S as indicated in Fig. 3. The contact arms pass over these contacts to make the circuits hereinafter described, as the semaphore moves successively from the vertical or "clear" position, through the

oblique or "caution" position, to the horizontal or "danger" position.

The track magnet Z has an iron core 131—130; and the auxiliary track magnet X an iron core 128—129. These track magnets are 79 located at a proper point of the left-hand block to afford indication to the train thereon of the condition of the right-hand block, which the train is about to enter.

The track magnets are disposed opposite 75 the corresponding train magnets, at as short an air gap as possible.

Operation.—The train relay B is shown in the normal or right-hand position. In this case, the locomotive not being over any 80 track element and traveling with the maximum speed range, current passes from the generator A through the wire 40', moving blade 1 of the relay B to the contact 13, wire 56, green light G, wire 45, back to the generator A; also by wire 40', moving blade 2 of the relay B to contact 16, wire 59, contact H, bridge arm c of the governor C, contact h, wire 43, magnet D, wires 44 and 45, back to the generator A, thus holding the air- 85 valve AV closed by energizing the magnet D; also by wire 40', wire 67, contact 22, moving blade 4, wire 68, coil 65 of the train magnet F, wire 64, moving blade 3, contact 19, wire 62, wire 40, back to generator A, 90 thus energizing the train magnet F. In train magnet F a magnetic field is thus established in the core in the direction 5—6—8—7, and by transformer action, the coil 35 is 95 energized to supply current at about 5 volts and in proper phase relation to the current flowing in the coil 34 of the relay B, thus retaining the elements of the relay B in the position shown.

When the right-hand block is clear, relay 105 TR, pole changer N and the switch P are in the position shown, a circuit being formed from the right-hand terminal of track magnet Z, by 109, contact 132, blade 107, wire 113, contact 112, arm 116, wire 117, switch 110 arm 118, contact 119 and plate 122, wire 123, coil 124 of the auxiliary track element X, wire 125, arm 116', contact 114, wire 115, blade 108, contact 133, wire 110, back to the coil 111; the coils X and Z thus being connected in series. When the locomotive passes over the track magnets so as to bring the train elements over the track elements, as shown in Fig. 4, the coil 124 of track element X will be energized from the train magnet E immediately above it, by a flux following the path 26—27—12—129—128—11. As coil 111 on the track element Z is in series with the coil 124 on the track element X, the current induced in coil 124 by the 115 said flux will energize the coil 111, and establish a flux flowing in the direction 130—131—10—8—7—9, and possibly 130, 131, 10, 6, 5, 9, and 130, depending upon the energization of the winding 65. As the coil 120 130

111 on the track element Z and the primary coil 65 of the train magnet F cause the flux to travel in the same direction, i. e., from 8 towards 7, the coil 35 will be energized with the same polarity and phase relation as under normal conditions while proceeding between block ends, and the relay B will be retained in its normal or right-hand position.

10 If the signal S be moved to the "caution" position, the pole-changer N is moved to the right-hand position of Fig. 1, and the arm 118 of the switch P to the position on 120. The pole-changer has now reversed the 15 relative direction of the current through the coil 111, in the manner customary for such pole-changers, and therewith the direction of the flux in the core of Z, so that the flux from 131 towards 130 opposes the flux from 20 5 towards 6, in the primary coil 65 of the train element F. By suitably dimensioning the parts so that the flux from Z is much stronger than that already existing in F, a reversal occurs of the current induced in 25 coil 35. The current in the coil 34 now counteracts the influence of the coil 42 since it is reversed in phase relation and the moving blades of relay B are drawn into the opposite or left-hand position. Current 30 now flows from generator A by wire 40' as follows: moving blade 1, contact 15, wire 58, yellow lamp Y, wire 45 and 41, back to the generator A; also by moving blade 2, contact 18, wire 61, contact M, bridge c— 35 and if the train speed be not above that for which the bridge arm c of the governor C is adjusted, i. e. a medium speed—by this bridge arm to contact h, wire 43, magnet D, wires 44, 45, 41, back to the generator (hence 40 if the train speed is not above a certain medium speed, the air valve is held closed, but if greater the valves are opened and the 45 brakes applied); also by wire 66, contact 21, moving blade 3, wire 64, coil 65 of train element F, wire 68, moving blade 4, contact 24, wires 62 and 40, back to the generator A, thus energizing the train element F in the opposite direction and causing the current induced in coil 35 to retain the relay 50 B in the left-hand or "caution" position.

When a train is on the right-hand block, the signal S is in the "danger" or stop position, the signal switch P is on point 121, and its circuit by wire 117, switch arm 116, wire 113, relay blade 107, contact 132, wire 109, winding 111, wire 110, contact 133, relay blade 108, wire 115, contact 114, switch arm 116', wire 125, winding 124, wire 123, back to contacts 120, 119 and bridge plate 60 122 is open. The train wheels and axles short-circuit the rails 101, 101', and the track relay TR no longer receives battery current, so that its armature falls and opens the contacts at 132 and 133. The coil 124 65 of the auxiliary track element X and coil

111 of track element Z are open-circuited. This likewise is the case upon failure or breakage of the connecting rails or wires. If the train on the left hand block passes over the track elements when they are in this condition, no current is supplied to the coil of the track element Z, but its core furnishes a magnetic path of less reluctance than the air-gap 69 of the train magnet element F, so that the flux travels by 5—6—8—10— 70 131—130—9—7—5, thus diminishing or annihilating the flux from 8 to 7, and preventing current being induced in the coil 35. The coil 34 no longer receives current, and the relay B falls to central or "danger" 75 position. Current now flows from the generator A by wire 40' as follows: moving blade 1, contact 14, wire 57, red light R, wires 45 and 41, back to the generator A; also by moving blade 2, contact 17, wire 80 60, contact L—and if the train speed is not greater than the predetermined low speed for which the bridge arm c is adjusted—by bridge arm c of the governor C, contact 7, wire 46, and 47, to push button 85 K and when the latter is closed by the engineer, by wire 48, magnet RM, wires 44, 45, and 41, back to the generator A, thus energizing the resetting magnet RM 90 and closing the contacts 50—51 and 52—52' 95 to short-circuit the push button K and keep magnet RM energized, and to keep the air-valve retaining magnet D energized. The engineer in pressing push button K is reminded that he is entering a danger zone; 100 which is also kept in his attention by the red lamp. A circuit is also formed from coil 65 by wire 68, moving blade 4, contact 23, wire 63, contact 20, moving blade 3, wire 64, back to coil 65, thus short-circuiting this 105 coil. The train may now proceed only at a low speed until a set of track elements corresponding to those at X and Z are encountered in a "clear" or "caution" position, so that coil 111 corresponding to coil 35 is 110 energized, and the relay B is moved to one of its end positions. The operation upon such an occurrence is that which has been described above.

If the train be travelling with the relay B in the "clear" position, and the safe speed for which the apparatus has been set is exceeded, the bridge arm H will be raised away from its contacts and open the circuit of the air valve retaining magnet D, so that 115 the air brakes will be applied.

The engineer, in using the push-button K and observing the signal lamps is continuously advised of the exact condition of the block head; and if a "danger" actuation 120 be delivered, his locomotive is unable to enter the block except after he had done the positive act of depressing K.

I claim:

1. In a train control system, the combina- 130

tion with the track rails, track battery, track relay, a normally deenergized track magnet adapted to be energized by a train magnet, and a second normally deenergized track magnet adapted to be energized by the current induced in a coil of said first track magnet flowing through the contacts of said track relay in closed position, of a constantly energized train magnet adapted to cooperate with said first track magnet, a second normally weakly energized train magnet adapted to be reversely energized by induction from said second track magnet, and a train-controlled relay actuated by current induced in a coil of said second train magnet.

2. A train control system comprising two track elements, a track relay and track battery adapted in the safe condition to close a series circuit including said track elements, a first and a second train element to respectively induce current in and receive current from said track elements in the safe condition, means to energize the coil of said first train element, and weakly energize the primary coil of said second train element, a secondary coil on said second train element adapted to have current induced therein by the weak energization, a train-controlling relay held in the safe condition by the current induced in said secondary coil, said train and track elements adapted to cooperate upon open-circuiting of the track relay contacts to prevent induction in said secondary coil and to bring said train controlling relay to a danger condition, and means associated with said relay to open-circuit said primary coil so long as said train relay is in the danger condition.

3. A train control system comprising a normally weakly energized train element, track means to assist the energization of said element, a train-controlling relay adapted to be brought to a safe condition upon such assistance, and contacts for said relay and means associated therewith to retain said relay in the safe and danger conditions determined at passage of the train over a track means.

4. A train control system comprising a normally energized first train element, a normally weakly energized second train element, a track element adapted to be energized by induction from said first train element and including a coil to have current induced therein by said energization, a semaphore and reversing switch, a second track element adapted to be energized by the current from the coil of said first track element in a direction reverse to that of the weak energization in the safe condition of said second train element when said semaphore and switch are in a caution condition, a train controlling relay including a position-retaining means and actuated by current induced in a secondary coil of said second train element, said second track element adapted to counteract the weak normal energization and establish a reverse energization in said second train element, whereby said train controlling relay is brought by the reversed current induced in the secondary coil of the second train element into the caution condition.

In testimony whereof he affixes his signature.

WILLIAM REED McCATHRAN.
